UNITED STATES PATENT OFFICE.

ROBERT J. KEE, OF OTTAWA, ONTARIO, CANADA.

LIFE-SAVING DEVICE.

Application filed March 19, 1923. Serial No. 626,186.

To all whom it may concern:

Be it known that I, ROBERT JOHN KEE, subject of the King of Great Britain, residing at 300 Cooper Street, in the city of 5 Ottawa, county of Carleton, Province of Ontario, in the Dominion of Canada, have invented a Life-Saving Device, of which the following is a specification.

My invention relates to a life saving device and is primarily intended for the use 10 of those at sea, and has for its object to provide an improved suit enclosing the body entirely and made buoyant by tubular chambers filled with kapok arranged vertically around the body and helmet.

It has been proposed to form a suit of 15 this kind comprising a jacket, pantaloons, helmet, sleeves, gloves and boots; and to line the interior of the same with wool or other 20 heat retaining material, while the body and helmet portions are made buoyant by vertical tubes of kapok. The leg portions are each separately inflatable by means of pipes through which air is blown through the 25 mouth of the occupant. The helmet is provided in the front with an air inlet and exit for breathing and ventilation, with means to prevent the entrance of water when momentarily submerged. The sleeve 30 portions are constructed in such manner as to allow the arms to be drawn into the interior of the suit for free use to convey food, stimulants, etc., to the mouth of the occupant.

According to my invention (which consists essentially in the particular construction, combination and arrangements of the parts hereinafter fully described), I subdivide the body and helmet portions into a 35 number of tubes or chambers distended with kapok, and the leg portions into a number of communicating tubes distended with air. The outer covering material is india rubber covered by cloth on either side and the 40 whole is lined on the inside with wool or other warm material.

The number of tubes forming the body of the suit would preferably be twelve, four disposed at the front and back, respectively, 45 and two at each of the sides, these tubes filled with kapok or some other light non-sinkable substance.

The construction of the helmet is tubular surrounding the back, sides, and top, and 50 these tubes are distended with kapok. The

helmet is cut away at the front opposite the face and furnished with an arched or outwardly convexed frame of aluminum or other light material, and provided with a window of plate glass for each eye. There 55 is an air conduit or channel from side to side of the helmet consisting of a breather made of aluminum or hard rubber, or other light material, the basis of which is two telescopic tubes, the outer one extending inside the helmet and the inner one extending through the helmet and a short distance at either end, which is closed by an automatic spring hinged lid. The air openings in the helmet are openings cut in the side 60 of these tubes and may be adjusted by the occupant by turning the outer tube on the inner tube and thus approximating the opening.

Each leg portion consists of a single pneumatic structure formed with tubular chambers and is provided with a small air pipe or tube for each leg extending interiorly into the helmet, by means of which this leg portion may be inflated by the lungs while 65 in the water.

The opening for enabling the suit to be put on and off is situated in front of the shoulders and is furnished with a steel clamp which is closed from within the suit. 70 This closure is reinforced from the inside by a waterproof tongue or apron. The body portion is slotted between the side tubes and provided with semi-dolman sleeves to enable the wearer to withdraw the arms and 75 use them inside the suit.

In the accompanying drawings Fig. (1) is a front elevation of the life saving device. Fig. (2) is a rear elevation of the same. Fig. (3) is a cross section through 80 the body of Fig. (1) drawn to a larger scale. Fig. (4) is a perspective view of the suit enclosing the occupant ready for the water. Fig. (5) is a perspective view of the same with the arms indrawn as may be done by 85 the occupant when in the suit. Fig. (6) is a clamp drawn to a larger scale used to close the outside of the entrance in front of the shoulders. Fig. (7) shows this clamp open in one-half its length. Fig. (8) shows 90 the clamp completely open. Fig. (9) is an elevation of the breather. Fig. (10) is an end view of the breather with the lid open. Fig. (11) is the brace used to convex the 95 front of the helmet. Fig. (12) is an alumini- 100

num funnel shaped vessel used inside the rubber excretion apparatus for the purpose of distending the same, and carried inside the suit.

5 The complete garment provided in accordance with this invention and as depicted in the accompanying drawings comprises a body portion A, arms portion B, gloves portion C, helmet portion D, leg portion E, 10 and boot portion F.

In the body portion A there is an opening in front of the shoulders for entering and emerging from the suit. This opening is closed by bringing the edges together and securing them by a steel clamp, and the closure is reinforced by a waterproof tongue or apron c shown inside. Figs. (6, 7, 8), represent the steel clamp used in closing this entrance or aperture. This clamp is semi-elliptical in shape, and extends directly across the suit in front of the shoulders. It is divided into sections of seven inches each a², which are connected or joined by hinges opening in one direction only, b² and c².

20 The hinge b² opens in the opposite direction to the hinge c². The clamp is closed at either end by a hinge d², which allows a separation of one-quarter of an inch. It is held closed in each section by a clasp e² which is closed

30 from the inside by the occupant after entering the suit, and it is lined with suitable rubber packing in order to shut out water. This clamp may be opened, if desired, in one half only to pass the hands in and out of the suit. The body portion A is suitably slotted at the sides for the attachment thereto of sleeves B of the semi-dolman type from which the wearer is enabled to withdraw the arms easily when desired, and use them inside the suit. The sleeves B are not provided with chambers but merely consist of water-tight casings and terminate in the gloves C integral with said casings.

40 The helmet covering D is at the back formed integral with or attached to the body portion of the suit. It has a series of vertical tubular chambers surrounding the sides, back and top distended with kapok.

45 The helmet D is cut away at the front opposite the face and distended with an arched or outwardly convexed frame of aluminum or other light material, Fig. (4) also see Fig. (11), and is provided with a window or plate glass for each eye b, Fig. (4). Opposite the mouth and nostrils, extending from side to side through the helmet, is the breather c, Fig. (4), represented in elevation by Fig. (9). This breather, Fig. (9) is composed of two telescopic tubes of aluminum

50 or other light material, two inches in diameter and eight to ten inches in length. The inner tube a', Fig. (9) extends from side to side through the helmet and contains one side opening only within the helmet. The outer tube b' forms a cuff or sleeve entirely

within the helmet and revolves on the inner tube at the will of the occupant of the suit. It contains two side openings to correspond with the opening on the inner tube. One of these openings c' is covered with wire gauze 70 (100 meshes to the sq. in.), so that by approximating the openings on the outer sleeve to correspond with the opening on the inner sleeve, a complete opening, or an opening covered by wire gauze, or a complete closure 75 may be attained. There are two flanges d' and e' on either end of the inner tube, the inner flange d' stationary and the outer flange e' screwed on in order to clamp between the two flanges the rubber material f' 80 of the helmet and in this way make it watertight. The inner tube extends a short distance outside the helmet at either end and the open end of this tube is closed by an automatic spring lid g'. The automatic lid g' is kept open by a spring h' and when pressure from a wave closes this lid it is immediately re-opened on hinge i'. Fig. (1) shows an end view of this automatic spring lid g' on hinge i' with a small stud j' for 85 closing with elastic band when packed.

90 Each leg portion E consists of a single pneumatic structure separate for each leg with boots F integral therewith formed with tubular chambers. These chambers are connected with each other so that each leg may be inflated by the lungs through the air pipe which extends through the body portion into the helmet, as shown by dotted lines Fig. (1).

95 In Figs. (1 and 2) e indicates a signal flag which may be worn on the top of the helmet to attract the attention of passing vessels.

Having now particularly described and ascertained the nature of my said invention and in what manner the same is to be performed, I declare that what I claim is:

100 1. A head covering arched in front in shape in a forward direction from the face of the occupant, and containing a glazed opening of plate glass for each eye, and having for means of ventilation two telescopic tubes extending through the arched front of the head covering from side to side opposite the mouth and nostrils of the occupant, and containing automatic spring ends outside the head covering and one side opening in the inner tube and two side openings in the outer tube inside the head covering, one of these side openings of the outer tube further protected by a wire gauze which admits air but 110 not water, and the openings on the outer tube are approximated to the opening on the inner tube by revolving the outer tube on the inner tube at the will of the occupant.

115 2. A complete combination garment throughout covering the entire body, in which an entrance in front of the shoulders is arranged through an aperture secured by a hinged rubber faced clamp, semi-elliptical in shape when closed and quadrangular 120

130

when open; this clamp being closed from the inside by the occupant and secured in this position by means of steel clasps; a belt shaped waterproof tongue of elastic rubber 5 material completely surrounding and with one edge attached, from within, to the edges of the aperture and secured by the clamp.

Signed at Ottawa this 29th day of February 1924.
